UNITED STATES PATENT OFFICE.

FRED G. NIECE, OF CLEVELAND, OHIO.

COIL FOR WIRELESS APPARATUS.

Application filed December 26, 1922. Serial No. 609,159.

This invention relates to an improved coil for radio apparatus and an improved method and means for winding and mounting the same. More particularly it comprises a coil having a minimum amount of distributed capacity for the wave length for which it is designed.

The value of air insulation in connection with coils for radio apparatus, particularly for receiving sets, has been recognized through the development of the honey-comb type of coil. Such coils, however, are best suited to long wave-lengths, the large air cores embodied in their design making them less effective for short wave reception than the spider-web type of coil. The spider-web type of coil, as heretofore constructed, requires an internal spider or similar support which reduces the efficiency of the coil by adding to its distributed capacity, although it has a much broader effective field than the honey-comb type of coil. Moreover, the honey-comb type of coil, as mounted in tapes and bands, is not free of capacity effects which seriously impair its value within the limit of its design.

The present invention has for its object to improve such coils in general and to obviate the difficulties referred to, and to produce a coil for radio apparatus having a minimum of distributed capacity and a maximum of self-inductance. It is also an object of the invention to suspend the coil of the circumferentially interwoven or intercoiled type by means of threads or similar flexible connections from a support spaced from the coil an adequate distance to provide an insulating air gap. Other objects of the invention will appear in the course of the following description. To the accomplishment of the foregoing and related ends, said invention, then, consists of the means and method hereinafter fully described and particularly pointed out in the claims.

The annexed drawing and the following description set forth in detail certain structure embodying the invention and method of making the same, such disclosed means constituting, however, but several of various structural forms and methods of making the same, in which the principle of the invention may be used.

In said annexed drawing:

Fig. 1 is a side elevation of my preferred type of coil and mounting in the usual vertical position as mounted on the panel of

a receiving set; Fig. 2 is a side elevation of means for winding a coil of the type shown in Fig. 1; Fig. 3 is a development of a section of the coil shown in Fig. 2, taken along the line 3-3 looking in the direction of the arrows; Fig. 4 is a side elevation of a coil of the type shown in Fig. 1 supported upon an internal mounting; Fig. 5 is a transverse longitudinal sectional view taken along the line 5-5 shown in Fig. 4; Fig. 6 is a side elevation of a modified type of coil, the windings corresponding to the Gramme ring; Fig. 7 is a transverse view of the Gramme type of coil illustrated in Fig. 6 when formed with a circular cross section; Fig. 8 is a view of said type of coil shown in Fig. 6 when formed with flattened sides so as to present an elliptical cross section; Fig. 9 is a perspective view showing a still further modified type of coil wherein the windings are of substantially figure 8 cross section, and Fig. 10 is a side elevation showing a coil supported upon an internal and external mounting.

As is clearly shown in Fig. 1 of the drawing, the preferred form of coil 1, and mounting made in accordance with the invention, is a coil of annular outline and narrow rectangular cross section which is suspended within an annulus 2 preferably formed of rigid insulating material of somewhat larger diameter than the coil. Flexible means 3 comprising thread of adequate strength is interlaced, as is clearly shown in the drawing, through the series of apertures 4 formed in the circumference of the supporting annulus and through the inner opening of the coil successively so as to support the coil concentrically with the mounting.

At one side of the annulus a supporting arm 5 is provided which may be hingedly or otherwise connected with the usual panel of a radio receiving set where said coil is to be used for such purpose. It is not intended, however, to limit the use of the coil to the particular purpose referred to, inasmuch as the invention contemplates the use of this type of coil wherever the reduction of distributed capacity to a minimum is indicated as proper designing. Opposite the point of connection of the supporting arm a finger pin 6 may be provided, said pin serving as one means of shifting the coil laterally where it is used in a three circuit or similar type of receiving set.

In Fig. 4 of the drawing is shown a modi-

fied form of mounting for the coil wherein the same is supported internally, instead of externally, by means of an internal disk 7, preferably formed of insulating material 5 spaced at every point out of contact with the coil. Flexible means 8 are used to hold said coil suspended in spaced relation about said disk by means of loops encircling said coil and passing through apertures 9 formed 10 adjacent the circumference of said disk. As shown in Figs. 4 and 5, said disk is adapted to be secured to the panel by means of a special support preferably formed of insulating material. Said support is preferably 15 an arm 11 having an integral disk-like terminal 12, to which the supporting disk 7 of the coil is attached by means of bolts 14 and spacing bushings 15.

In place of either of the methods of 20 mounting the support heretofore mentioned, the coil may be supported from both internal and external supports of the character described as is shown in Fig. 10, through the interlacing of flexible connections 3, 8, between said coil and said supports. The form 25 first described, however, is my preferred form, inasmuch as it secures greater rigidity for the outer edges of the coil and serves as a guard for the coil itself, as well as removes as far from the coil as possible all 30 elements which would seriously affect its distributed capacity.

In Figs. 6, 7 and 8, there is illustrated a coil 20 of the Gramme ring type of construction 35 which may be substituted for the preferred type of coil already described. As shown in Figs. 6 and 7, the coil preferably is formed of a single wire wound about a circle of a given diameter and continued as a helical winding until an adequate amount of 40 wire has been incorporated in the coil for the purpose for which it is designed. In order to diminish the air core of the coil, as well as increase its effective field with respect to adjacent inductances, the coil just described 45 may be formed with flattened sides 21, as shown in Fig. 8 of the drawing.

The type of winding 22, shown in Fig. 9 of the drawing, has the advantage of the circular form of Gramme ring coil and at the same time requires no flattening of the sides, inasmuch as the figure 8 outline of the windings serves to present a coil of narrow transverse dimensions. It is obvious that the 55 magnetic fields of the outer and inner parts of the coil are reversed with respect to each other and mutually interact to enhance the total inductance of the coil.

While the invention is not restricted to one 60 method of winding the coil, there is included herein a method which necessarily results in the production of the preferred type of coil.

It has been found that employing a central cylindrical member or mandrel 31, and 65 placing wooden or metal pegs 32 in aper-

tures 33 formed about a circumferential line thereof, after the manner of the spokes of a wheel, and winding a wire 34 about two such pegs 35, 36, crossing to the opposite side and winding said wire about the two adjacent pegs 37, 38, and repeating the process until the circuit is complete, affords one of the simplest methods of constructing a coil which will have a high degree of rigidity when suitably tied with thread. An uneven number 70 of pegs is provided so that when the circuit of the cylinder has been completed the second layer of winding will be about a different pair of pegs than the first and the winding will be shifted one peg alternately 75 throughout the structure of the coil. When the coil is built up to the desired size, the pegs are successively withdrawn from the apertures, the cylinder or mandrel is removed from the center of the coil, and thread 80 of suitable strength is interlaced about the windings passing downwardly through each aperture formerly occupied by a peg and upwardly through the adjacent aperture thereto and thence downwardly once more 85 through the original aperture and in a similar manner throughout the circumference of the coil, certain of the loops 41 so formed extending downwardly and the adjacent loops 42 formed in said winding thread extending 90 upwardly. The ends of the thread are securely tied and a coil, having each of its circumferential layers firmly held to the adjacent layers, is provided. The coil so formed 95 is self-supporting and of a very high degree 100 of rigidity. The coil is then connected in spaced relation to its mounting, as has already been described, for use in whatever unit of radio apparatus that may be desired.

Other forms may be employed embodying 105 the features of my invention instead of the one here explained, change being made in the form or construction, provided the elements stated by any of the following claims or the equivalent of such stated elements be employed, whether produced by my preferred method or by others embodying steps equivalent to those stated in the following claims.

I therefore particularly point out and distinctly claim as my invention:—

1. In an article of the character described, the combination of an annular coil the windings of which co-operate to form loops, a rigid mounting therefor spaced from said coil, and means for connecting said coil at a plurality of points with said mounting.

2. In an article of the character described, the combination of an annular coil the windings of which co-operate to form loops, a rigid mounting therefor uniformly spaced from said coil, and flexible means for connecting said coil at a plurality of points with said mounting.

3. In an article of the character described, the combination of a circumferentially inter-

woven coil, a rigid mounting therefor spaced from said coil, and means for connecting said coil at a plurality of points with said mounting.

5 4. In an article of the character described, the combination of a circumferentially interwoven coil, a rigid mounting therefor positioned outwardly of and spaced from said coil, and means for connecting said coil at 10 a plurality of points with said mounting.

5. In an article of the character described, the combination of a circumferentially interwoven coil, a rigid mounting therefor po-

sitioned inwardly of and spaced from said coil, and means for connecting said coil at a 15 plurality of points with said mounting.

6. In an article of the character described, the combination of a circumferentially interwoven coil, a rigid mounting therefor positioned outwardly and inwardly thereof and 20 spaced from said coil, and means for connecting said coil at a plurality of points with said mounting.

Signed by me, this 18th day of December, 1922.

FRED G. NIECE.
